UNITED STATES PATENT OFFICE.

CHRISTIAN E. BAKER, OF CHICAGO, ILLINOIS, ASSIGNOR OF ONE-HALF TO
CHARLES A. EGGERT, OF MUSKEGON, MICHIGAN.

FIRE-ESCAPE.

SPECIFICATION forming part of Letters Patent No. 278,847, dated June 5, 1883.

Application filed February 20, 1883. (No model.)

To all whom it may concern:

Be it known that I, CHRISTIAN E. BAKER, of Chicago, in the county of Cook and State of Illinois, have invented a certain new and useful 5 Improvement in Fire-Escapes; and I do hereby declare that the following is a full, clear, and exact description thereof, reference being had to the accompanying drawings, and to the letters of reference marked thereon, which form 10 a part of this specification.

This invention has for its object to produce a device by which in case of fire persons can lower themselves to the streets from the upper floors of hotels, factories, or other high buildings with perfect safety; and it consists in the connection of a basket by an intermediate tackle or differential spools with a piston that travels in a pipe, the speed of which is controlled by the escapement of water from above such piston, while the return-lift of the empty basket is caused by a vacuum formed below the piston, all as hereinafter more fully described and specifically claimed.

In the accompanying drawings, Figure 1 represents an elevation of the entire apparatus; Fig. 2, a vertical section of the upper portion of the pipe, and Fig. 3 a vertical section of the lower portion of the same.

Corresponding letters in the several figures 30 of the drawings designate like parts.

A denotes a wrought or cast iron or brass pipe, that is bored out true cylindrical, with its bottom end closed hermetically by a cover, a. The top end of this pipe A is also closed by a 35 cap, b, that is screwed upon it, and is tapped at its sides by one or more small cocks or faucets, c. Upon this pipe A, between cap b and a flange, d, is secured the bottom rim of a globular or otherwise shaped reservoir, B. This 40 pipe A has a ring-flange, e, screwed upon its lower portion, that by bolts f connects such pipe with a plate, C, which is rigidly secured upon the floor of the hall or room in the building, and by bracket-clamps o such pipe A is 45 fastened to the wall of the room. A small air-cock, g, is tapped through cover a of pipe A. A piston, D, provided with suitable packing-rings, is snugly fitted into cylinder A to move up and down therein. This piston has a loop, 50 h, for coupling the end of a wire rope, E, that is projected through a central hole in cap b, is

passed over a sheave, i, and is thence coupled to block j of a tackle, F, that is placed under the ceiling of the hall or room. The opposite block, K, of tackle F is rigidly coupled to the 55 inside of the wall of the building. The fall end of the tackle-rope m is passed through a hole in the wall and over a sheave or pulley, n, that is secured under the cornice, veranda, or to a bracket, G, of the outer wall of the building, 60 and a basket or box, H, is suspended to the end of such rope m.

The *modus operandi* of the apparatus is as follows, to wit: The piston D is pushed to the bottom of pipe A, while air-cock g is open to expel 65 all the air below such piston, and at the same time the pipe A above the piston is filled with water. Next the air-cock g is closed entirely, and the faucets c are partly closed. A person now mounting the basket H will move downward by his or her weight, and will cause an upward movement of the piston D, which movement is regulated by the size of openings in faucets c, for the water to escape from pipe A into reservoir B. The velocity of basket H relative to that of piston D is multiplied by the number of rovings of rope m through blocks j and k of the tackle F, which is to be proportional to the length of pipe A relative to the elevation 70 above the street, in such a manner that by the 75 time the piston D has reached the upper end of pipe A the basket H has arrived at the ground. While the piston D is thus pulled upward and is forcing the water out of pipe A into reservoir B a vacuum will be formed below such piston 80 D, since no air can leak through the bottom of such pipe, and since the water in the upper portion of the pipe will prevent the leakage of air by the piston. As soon as the basket H is relieved of its load it will be elevated again to 85 its original position by the atmospheric pressure pushing the piston D to the bottom end of cylinder A again, the return movement of such basket being of about the same velocity with which it was lowered, or proportional to the 90 speed with which the water can enter pipe A again through faucets c. After the basket H is 95 arrived at the top again a second person can occupy it to lower himself in a like manner, and so on continuously until everybody 100 has made his escape from the burning building.

As will be noticed, this device or apparatus is very simple in its construction, is entirely safe and reliable, and is always ready for use in case of emergency.

5 The pipe A can be located any distance away from the place where the basket is to be suspended, and can be placed into any nook or corner where it is out of sight.

In place of a tackle, differential spools or 10 gearing can be employed with equal advantage for proportioning the difference of travel between basket H and piston D. Water being a non-elastic fluid of which only a certain amount can pass through an opening within a certain 15 time, with but a small variation caused by different pressures, the down speed of the basket will be but very little increased by several persons mounting the basket at the same time.

What I claim is—

20 1. In a fire-escape, the combination of a basket with a piston traveling in a pipe, the speed of which is regulated by the escape of water from the pipe above such piston, and that will elevate the empty basket again by atmospheric

pressure brought about by a vacuum formed 25 below such piston, all constructed and arranged to operate substantially as and for the purpose set forth.

2. In a fire-escape, the pipe A, having faucets 30 c and reservoir B, in combination with piston D, that by ropes E m and a multiple purchase connects with basket H, the same being constructed and arranged to operate substantially as and for the purpose set forth.

3. In a fire-escape, the pipe A, having faucets 35 c and reservoir B, in combination with piston D, that by rope E and tackle F connects with basket H, all constructed and arranged to operate substantially as and for the purpose set forth.

40 In testimony that I claim the foregoing as my invention I affix my signature in presence of two witnesses.

CHRISTIAN E. BAKER.
